(57) **CLAIM**

The ornamental design for a pet seat cover, as shown and described.

DESCRIPTION

FIG. 1 is a side perspective view of a pet seat cover showing an outer flap in a down position and an inner flap with a window in an up position.

FIG. 2 is a side perspective view of the pet seat cover showing the outer flap and the inner flap in the down position.

FIG. 3 is a perspective view of the pet seat cover showing the outer flap and the inner flap in the up position.

FIG. 4 is a top view of the pet seat cover when the panels of the pet seat cover are folded down.

FIG. 5 is a bottom view of the pet seat cover when the panels of the pet seat cover are folded down.

FIG. 6 is a right side view of the pet seat cover when the panels of the pet seat cover are folded down.

FIG. 7 is a right side view of the pet seat cover when the panels of the pet seat cover are folded up.

FIG. 8 is a left side view of the pet seat cover when the panels of the pet seat cover are folded down.

FIG. 9 is a left side view of the pet seat cover when the panels of the pet seat cover are folded up.

FIG. 10 is front side view of the pet seat cover when the panels of the pet seat cover are folded down.

FIG. 11 is a front side view of the pet seat cover when the panels of the pet seat cover are folded up.

FIG. 12 is a rear side view of the pet seat cover when the panels of the pet seat cover are folded down.

FIG. 13 is a rear side view of the pet seat cover when the panels of the pet seat cover are folded up; and,

FIG. 14 is an enlarged view of the area indicated in FIG. 1. The portions of the pet seat cover depicted in the figures in broken lines form no part of the claimed design. The double dashed lines along the zipper teeth in FIGS. 1 to 5, 11, and 14 represent stitching, and form no part of the claimed design.

1 Claim, 10 Drawing Sheets
